UNITED STATES PATENT OFFICE.

WALTER C. LINDEMANN, OF MILWAUKEE, WISCONSIN, ASSIGNOR TO A. J. LINDEMANN & HOVERSON COMPANY, OF MILWAUKEE, WISCONSIN.

ELECTRIC HEATING DEVICE.

Application filed March 28, 1922. Serial No. 547,585.

To all whom it may concern:

Be it known that I, WALTER C. LINDEMANN, a citizen of the United States, and a resident of the city of Milwaukee, in the county of Milwaukee, State of Wisconsin, have invented certain new and useful Improvements in Electric Heating Devices, of which the following is a specification.

The improvements relate to electrical heating devices, for cooking or other purposes, and particularly to devices of this kind in which grids or plates with openings therein are employed to support cooking utensils, food, or other things to be subjected to the heat of electric resistance elements arranged beneath the grid. Among the objects of the improvements are the production of a construction having greater strength, durability and heating efficiency, and in which the parts may be assembled or dismembered for repairs or other purposes with facility, and may be made in various forms. Another and more specific object is to so form and arrange the frame of the heating unit and its insulators, by which the electric resistance heating element is held, that they may be manufactured by methods calculated to produce a simple, strong, and effective unit at a minimum manufacturing cost, and treated before being assembled, to resist the action of heat, electric current and fluids to which they are subjected in use.

The improvements are illustrated in the accompanying drawings, in which Figure 1 is a plan of a heating unit embodying the improvements; Fig. 2 is a vertical section of the same on the line 2—2 of Fig. 1, looking in the direction indicated by the arrows in that figure; Fig. 3 is a view similar to Fig. 2 of the upper part of the metallic frame with the insulating and heating element holders removed; Fig. 4 is a detail of one of the parts of an insulating holder; Fig. 5 is a plan of a modified form; Fig. 6 is a vertical section of the same on the line 2—2 of Fig. 5, looking in the direction indicated by the arrows in that figure, and Fig. 7 is a vertical section of a modified form of holder.

Referring to the construction illustrated in Figs. 1 to 4 inclusive, the frame of the heating unit comprises a plate 1, in which is formed centrally a grid or grate com-

posed of a central portion 2 with arms or webs 3 radiating therefrom, concentric rings 4 and 5 and connecting webs 6 and 7 between these rings and between the outer one and the plate 1. It also has flanges 8 depending from its edges adapted to receive and hold the similar upstanding flanges 9 of the bottom plate 10, thereby forming a box-like enclosure for the other parts. The lower plate of the frame or casing may be provided with suitable feet, if desired, and is of the same form as the upper plate, both plates being preferably stamped to produce the grid.

In making the two halves of the housing it is preferred to take a sheet of metal and stamp and punch it by means of suitable dies, so as to form the sides thereof and the openings of the grid; and in this operation a sufficient quantity of the metal is permitted to remain along the edges of the openings to form not only the top and bottom grid members but to form, in the stamping operation, depending flanges 11, 12, 13, 14, 15, 16, 17, 18, 19, 20, 21, 25, etc., at the edges of said members, which not only serve to add great strength and durability, but form holders to receive half blocks 22, 22^a forming the insulating support for the electric resistance elements 23 and 24. At the corners the flanges may be cut away as shown at 30 to facilitate the stamping operation.

The blocks 22, 22^a are made of porcelain or other suitable electric insulating substance, and are relatively light but strong and of sufficient width to space and insulate the resistance elements, while at the same time they absorb a minimum of heat and permit a maximum of the heat of the said element to be utilized for cooking or heating operations. The electric resistance elements 23 and 24 extend through the apertures 26 of the insulating and supporting blocks composed of the two complementary parts 22, 22^a and span the spaces of the grid, being connected with service wires by means of binding posts 27, 28, and 29, having electrical contact devices thereon. Flanges 8 and 9 have open slots for the binding posts.

The two parts of the housing, including the grids, as will be seen, are each made of a single piece of sheet metal, and, before as-

sembling these parts may be coated with vitreous enamel or other suitable protective coating.

For units designed to be used with low temperature resistance elements the flanges of the grid members may be made longer and curled at their lower edges, as shown at 31 (Fig. 7), so as to form a holder with an aperture 32 to receive the said element, where 10 the construction of the grid and the disposition of the resistance element permit it. In any case the said resistance element may be coiled, crimped or shaped in any suitable manner to produce the desired result.

15 In the modification of Figs. 5, 6, and 7 the grid is of rectangular form, and the longitudinal flanges 34 of the grid bars 33 receive and hold insulating supports 35 extending longitudinally thereof and supporting resistance wires 36, these supports having a plurality of recesses, which, when the two halves of the support are placed together, form wire-receiving apertures 37. Bolts 38 may be passed through the upper 20 and lower plates 39 and 40 of this form, as well as through the plates of the preferred form, if desired, to hold them securely together. The form of resistance element support shown in Fig. 7 is peculiarly applicable 25 to this modification, but where the wires are run crosswise through the support it will be necessary to form longitudinal complementary recesses therein similar in form to those of the supports 35, so as to produce apertures 30 for the said wires.

In assembling the unit the bottom member of the housing is first made up by placing half blocks in the holding flanges. The electric resistance element is then laid in the recesses of the blocks and the upper half 40 with its half blocks then placed thereon and secured. In disassembling the unit this operation may be reversed; and it will be seen that the construction and arrangement is such 45 that the unit may be taken apart for the purpose of cleaning it or renewing the wires or other parts and put together again quickly and with a small expenditure of labor.

The top or bottom member of the housing, or both, may, if desired, be cast instead of stamped, and may be made of any suitable material, and the details of construction and arrangement of the parts may be varied to a certain extent without departing from 50 the scope of the invention.

What I claim is:

1. An electric heating unit comprising upper and lower sections forming a housing for the unit, each part provided with a portion of a resistance element supporting and insulating device, upper and lower insulating device parts supported in said housing parts, each having a recess therein, and the two recesses formed to produce when 55 brought opposite each other apertures for

receiving a resistance element, and a resistance element in said apertures and supported by the insulating device, and means for securing the said upper and lower parts together. 70

2. In a device such as that specified in claim 1, holding flanges extending from each housing part toward the other and opposed to each other, said flanges being arranged in spaced relation to receive the said 75 insulating parts.

3. A device such as that specified in claims 1 and 2, in which the flanges are integral with their respective housing parts.

4. In a device such as that specified in 80 claim 1, engaging portions on the upper and lower housing parts constructed and arranged to telescope when the said parts are brought together.

5. A device such as that specified in claim 85 1, having openings in the said housing parts formed by punching out the metal thereof having strips between them forming a grid, and a portion of the metal displaced in forming said openings turned inwardly and forming insulator holding flanges. 90

6. A device such as that specified in claim 1, in which the upper and lower housing parts are formed of flat sheets of material punched and stamped to form therein grids 95 having relatively large openings and strips of material between them and the edges of said openings turned inwardly to form strengthening flanges depending therefrom, and forming holders for the insulating device. 100

7. In a device such as that specified in claim 1, a coating of vitreous material on the upper surface of the upper housing part.

8. An electric heating unit comprising a 105 metal form having upper and lower sections secured together, an electric resistance heating element between said sections, and insulating holders for said element secured in place by and between said sections, said sections having grid openings therein and depending flanges at the edges of grid openings. 110

9. In combination with the mechanism specified in claim 8, a coating of vitreous enamel applied to one of said sections and covering the surfaces of the same. 115

10. In the device specified in claim 8, the said flanges projecting inwardly from said sections and receiving and holding said 120 insulating holders.

11. In the device specified in claim 8, the said flanges formed of metal displaced by punching and stamping the metal of one of the sections, said flanges receiving and holding insulating holders. 125

12. In the device specified in claim 8, the said flanges extending inwardly from grid forming openings with which one of said sections is provided, said flanges being inter- 130

gral with the metal at the edges of said openings and securing the insulating holders.

13. An electric heating unit comprising a metal form having upper and lower sections secured together, an electric resistance heating element between said sections, and insulating holders for said element secured in place by and between said sections, said insulating holders being made in a plurality of sections and one holder section carried by each of the said first named upper and lower sections.

14. An electric heating unit comprising

two plates provided with a series of openings and strips or bars between said openings, said strips or bars having depending portions spaced apart, insulating holders positioned between the depending portions of said bars and an attenuated electric resistance element held between the said insulating holders and extending throughout the device.

Witness my hand this 22d day of March, 1922, at the city of Milwaukee, in the county of Milwaukee, State of Wisconsin.

WALTER C. LINDEMANN.
